UNITED STATES PATENT OFFICE.

WILLIAM RICHARD WHITE, OF BLOOMINGTON, ILLINOIS.

DESIGN FOR AN OPERATING-BAR FOR GATE-LATCHES.

SPECIFICATION forming part of Design No. 31,550, dated September 26, 1899.

Application filed September 1, 1899. Serial No. 729,259. Term of patent 14 years.

To all whom it may concern:

Be it known that I, WILLIAM RICHARD WHITE, a citizen of the United States, residing at Bloomington, in the county of McLean and State of Illinois, have invented and produced a new and original Design for an Operating-Bar for Gate-Latches, of which the following is a specification, reference being had to the accompanying drawings, forming part thereof.

Figure 1 is a side view of an operating-bar for a gate-latch, showing my new design; and Fig. 2 is a cross-section thereof on the line 2 2, Fig. 1.

The leading feature of my design consists of a bar having a loop in the line thereof and a downwardly-deflected section at one side of the loop, the outer end of the deflected section being substantially parallel with the body of the bar.

Thus, referring more particularly to the drawings, A indicates the bar, which is doubled upon itself to form a loop a, and b is the downwardly-deflected section thereof, which terminates in a relatively short end portion c, lying substantially parallel to the body of the bar.

Having described my invention, what I claim as new, and desire to secure by Letters Patent, is—

The design for an operating-bar for a gate-latch, substantially as herein shown and described.

In testimony whereof I have signed my name to this specification in the presence of two subscribing witnesses.

WILLIAM RICHARD WHITE.
